BIGELOW CARPET COMPANY, OF MASSACHUSETTS.

DESIGN FOR CARPET AND BORDER.

SPECIFICATION forming part of Design No. 24,569, dated August 13, 1895.

Application filed June 15, 1895. Serial No. 552,958. Term of patent 3½ years.

To all whom it may concern:

Be it known that I, WILLIAM F. BROWN, a subject of the Queen of Great Britain, and a resident of Newark, in the county of Essex and State of New Jersey, have invented a new and original Design for a Carpet and Border, of which the following is a specification.

The invention comprises two parts—namely, the design A for a carpet and the design B for a border; and I do hereby declare that the drawing accompanying this specification conveys to any one a clear understanding of the same, and is sufficient to enable such person to use my invention.

The design A is characterized by floral clusters having large curving stemwork of leaf and floral forms constituting the leading feature thereof, and the design B is characterized by floral clusters connected by festoons of leaf

and floral forms, constituting the leading feature thereof.

What I claim, and desire to secure by Letters Patent, is—

1. In a design for a carpet, the body A substantially as shown.
2. In a design for a carpet, the border B substantially as shown.
3. The design for a carpet, comprising the body A and the border B substantially as shown.

In testimony whereof I have signed my name to this specification in the presence of two subscribing witnesses.

WILLIAM F. BROWN.
